George S. Cox
BY Frank D. Busser
ATTORNEY,

UNITED STATES PATENT OFFICE.

GEORGE S. COX, OF PHILADELPHIA, PENNSYLVANIA.

HAIRCLOTH-LOOM.

1,094,882.

Specification of Letters Patent. Patented Apr. 28, 1914.

Application filed July 25, 1913. Serial No. 781,064.

To all whom it may concern:

Be it known that I, GEORGE S. COX, a citizen of the United States, residing at Philadelphia, county of Philadelphia, and State of Pennsylvania, have invented a new and useful Improvement in Haircloth-Looms, of which the following is a full, clear, and exact description, reference being had to the accompanying drawings, which form a part of this specification.

My invention relates to looms, and particularly to that type of loom adapted to the manufacture of hair-cloth and similar goods, wherein the weft is prepared in separate strands or picks of substantially equal length or slightly longer than the width of the goods to be woven, and wherein a nipper is provided having a pair of jaws at each end or at one end by means of which picks of hair are pulled from one side to the other of the loom at each reciprocation or semi-reciprocation of the nipper across the reed. A loom of this type is set forth in Letters Patent No. 1,026,430, issued to me May 24, 1912. The object of the invention of that patent was to provide means for imparting to the nipper a differential movement comprising a gradual retardation at the end of each traverse and a gradual acceleration at the beginning of each traverse. To this end certain actuating mechanism for the nipper was provided, the same comprising a gear on the crank-shaft in driving engagement with a gear on an auxiliary shaft, a bevel gear on the auxiliary shaft in driving engagement with a bevel gear on a third shaft turning in bearings on a stand, a crank on the third shaft, a rack-bar attached to the crank and engaging a pinion on a fourth shaft turning in bearings on a second stand, an eccentric pulley on the fourth shaft, and a flexible connection secured between its ends to the nipper and secured at its opposite ends to the pulley around which it is adapted to wind as the pulley is oscillated, thereby imparting to the nipper its reciprocating traverse movement. The pulley is so constructed, arranged and proportioned as to impart to the nipper the differential movement aforesaid. The construction set forth in said patent is operative, but unless the driving mechanism is constructed with a considerable degree of care and accuracy, certain defects in the operation tend to develop, which I have discovered arise by reason of the tendency to lost motion in the driving connec-

tions between the crank shaft and the pulley. This lost motion I have found to be due partly to the number of transfers in the drive and partly to the transfer of the axis of rotation of the driving parts from one parallel to the crank-shaft to one at right angles thereto.

The object of the present invention is to simplify the driving connections between the crank-shaft and the pulley, eliminate or radically reduce lost motion, and avoid changing the direction of the axis of rotation of the driving parts, and thereby eliminate the defects of operation hereinbefore mentioned. To this end I have devised the driving connections shown in the accompanying drawings, in which—

Figure 1 is a section through the loom, showing a front view of the part of the loom embodying my invention; Fig. 2 is a side elevation of the same; Fig. 3 is an enlarged detail view showing the means of attaching the flexible connection to its operating pulley.

10 is the loom frame; 11 the reed; 12 the lay carrying trunnions 13 by means of which the lay is pivoted in bearings 14 in the loom frame; and 15 the crank-shaft carrying cranks 16 and links 17 by means of which the lay is oscillated. Secured direct to the crank-shaft is a crank 18. To the crank 18 is adjustably secured one end of a rack-bar 19 the other end of which has a rack 20 engaging a pinion 21 on a shaft 22. The shaft 22 has its bearing at one end in the loom frame and at its other end in a stand 23. As shown, this shaft 22 may be simply a prolongation of one of the trunnions 13 of the lay. On the shaft 22 is loosely sleeved a frame 24 in which turn a pair of idler rollers 25 engaging the face of the rack-bar opposite its toothed face and adapted to hold the rack in driving engagement with the pinion. On the shaft 22 is a pulley 26. For purposes of simplification, this pulley is shown as mounted concentric to the shaft, as the present invention is not concerned with the special method of mounting the pulley.

27 is a flexible connection, which may conveniently be an ordinary rope or sprocket chain, opposite ends of which are adapted to wind more or less about the driving face of the pulley. The ends of the rope may be fastened to the pulley in any convenient manner, as, for example, each rope end may be passed through a radially-extending hole

in the pulley face and secured to the end of a threaded bolt 28, the bolt extending through a flange on an angle plate 29 secured to the pulley. An adjusting nut 30 and a holding nut 31 engage the bolt on opposite sides of the flange. The opposite ends of the rope connect with the face of the pulley preferably side by side and the two end sections extend around the face of the pulley 10 in opposite directions and thence upwardly, one end section extending over a roller 32 and thence longitudinally of the loom toward one end of the lay and shuttle race and under and over a pulley 33, while the other section 15 extends over a roller 34 and thence longitudinally of the loom toward the other end of the lay and shuttle race and under and over a roller 35. The rollers or pulleys 32, 33, 34 and 35 are all mounted to turn in 20 bearings on the lay. The middle part of the rope extends along a cut-away portion of the lay beneath the shuttle race. The rope is secured to a slide 36, which is secured to the nipper or shuttle 37 and operates in a track 25 in the overhanging end of the lay.

I have shown a shuttle or nipper comprising a stick having a pair of jaws 38 at one end only, the same operating to pull picks of hair from one side to the other at each semi-30 reciprocation. It will be understood, however, that the invention is not limited in its application to a shuttle of this type.

It will be observed that the arrangement is such that the pulley 26 makes one complete oscillation back and forth and the shuttle one complete reciprocation back and forth along the shuttle race during each complete rotation of the crank-shaft 15; this being necessary where the invention is applied, as shown, to a nipper stick having jaws at one end only and operating to pull picks of hair from one side to the other in its movement in one direction only.

It will be understood that when the lay 45 starts to beat in one direction, the empty shuttle starts on its movement from right to left and that as the lay completes its movement in this direction, the nipper jaws travel through the warp shed and grasp a 50 pick of hair, that as the lay starts to beat in the opposite direction, the shuttle starts on its return movement, during which it inserts a pick of hair, and that the jaws pass beyond the warp shed as the lay completes 55 its stroke. By adjusting the rack bar 19 on the crank 18, the extent of the angular movement of the pulley 26 may be varied, and by this means the length of travel of the shuttle may be varied to adapt it to the 60 weaving of goods of different widths.

It will be observed that the driving mechanism between the crank-shaft and the shuttle-actuating pulley is much simplified over that disclosed in my said patent, in that 65 there are eliminated two shafts and two

pairs of gears. Further the axis of the pulley shaft is arranged parallel to the axis of the crank-shaft, the two sections of the flexible connection being arranged to feed upward from the shuttle-actuating pulley, thereby permitting the idler pulleys to be arranged so as to divert the middle portion of the flexible connection into the position necessary to enable it to reciprocate the shuttle.

While I have referred to the flexible connection as a single rope attached at or near its middle portion to the shuttle, it is obvious that the rope may be formed in two separate sections adjacent ends of which are attached to the shuttle; Fig. 1 serving to illustrate this equivalent construction if it be assumed that the slide 36 is the common point to which such adjacent ends are attached.

Having now fully described my invention, what I claim and desire to protect by Letters Patent is:

1. In a loom, the combination with the crank-shaft, the pivoted lay and the shuttle race carried thereby, and the shuttle, of shuttle reciprocating means comprising a pulley turnable on an axis parallel to the crank-shaft, a crank on the crank-shaft, a pinion on the pulley shaft, a rack bar attached to the crank and in driving engagement with said pinion, a flexible connection engaging the shuttle, the opposite ends of the flexible connection connecting with the pulley face and winding about the same in opposite directions, and guide rollers, engaged by the flexible connection, between the shuttle and each end of the flexible connection connected to the pulley.

2. In a loom, the combination with the crank-shaft, the pivoted lay and the shuttle race carried thereby, and the shuttle, of shuttle reciprocating means comprising a pulley turnable on an axis parallel to the crank-shaft, a pinion on the pulley shaft, a rack bar attached to the crank and in driving engagement with said pinion, a flexible connection engaging the shuttle, the opposite ends of the flexible connection connecting with the pulley face and winding about the same in opposite directions and directly feeding therefrom in an upward direction, a pair of guide rollers arranged above the pulley, and a pair of guide rollers arranged above and on opposite sides of the first pair of guide rollers and below the level of the shuttle race, one roller of each pair engaging one section of the flexible connection and the other roller of each pair engaging the other section of the flexible connection.

3. In a loom, the combination with the crank-shaft, the pivoted lay and the shuttle race carried thereby and the shuttle of shuttle reciprocating means comprising a pulley turnable on an axis parallel to the crank

shaft, a pair of guide rollers directly above the pulley, a pair of guide rollers above and on opposite sides of the first pair of guide rollers and below the level of the shuttle race, a flexible connection connected to the pulley face and winding about the same in one direction and thence extending upward to one of the first pair of rollers, thence longitudinally of the shuttle race to one of the second pair of rollers, thence longitudinally of the shuttle race and attached to the shuttle, thence longitudinally of the shuttle race to the other of the second pair of rollers, thence longitudinally of the shuttle race to the other of the first pair of rollers, thence

downward to and winding about the pulley face in a direction opposite to the direction of extension of the first end of the flexible connection about the pulley face, a crank on the crank-shaft, a pinion on the pulley shaft, 20 and a rack-bar attached to the crank and in driving engagement with said pinion.

In testimony of which invention, I have hereunto set my hand, at Philadelphia, on this 16th day of July, 1913.

GEORGE S. COX.
